GALLEY FOR LINE CASTING MACHINES

Filed Dec. 18, 1930

UNITED STATES PATENT OFFICE

EDMUND M. GOODEBODY, OF BELLEROSE, NEW YORK, ASSIGNOR TO INTERTYPE CORPORATION, OF BROOKLYN, NEW YORK, A CORPORATION OF NEW YORK

GALLEY FOR LINE CASTING MACHINES

Application filed December 18, 1930, Serial No. 503,287, and in Germany January 18, 1930.

The present invention relates to improvements in line casting machines of the general class shown and described in U. S. Letters Patent No. 436,532 granted September 16, 1890, to O. Mergenthaler, and it relates more particularly to the galley used on such machines to receive the type bars or slugs cast in the machine and for stacking them in a row in the order in which they are cast, the invention relating more especially to the so-called "outside" galleys used on such machines which are arranged on the outside of the framework of the machine and in which the type bars or slugs are received and positioned with their type faces directed upwardly.

Galleys of this kind as heretofore used receive the type slugs from the usual ejecting means on the machine while the slugs are standing on end, and while the slugs are passing into the galley they are turned to bring their type faces uppermost, and slugs of the usual lengths are satisfactorily received in this manner by galleys of this kind, but such galleys have been found to be incapable of properly receiving and positioning short measure slugs such as those of 4 to 6 ems in length, with the result that it has been the general practice, when very short lines of type are required, to cast the type matter on slugs of considerably greater length than required by such matter, they being made for example 10 or 12 ems in length, so that they will be properly received and positioned in the galley, and the excess length or blank portions of the slugs were subsequently sawed off, but such a practice is objectionable owing to the time and the labor required.

The primary object of the present invention is to provide means whereby short measure slugs ejected through the usual ejecting passage by the usual ejecting means on the machine will be received and so guided and directed as to deposit such slugs in the galley with their type faces directed upwardly, thus obviating the necessity of casting such slugs of excess length and of removing the excess or blank portions thereof as heretofore practiced.

Another object is to provide such means

for receiving and positioning short length slugs which may be readily actuated by the normal movement of a usual part of the machine.

A further object of the invention is to provide an attachment carrying the short length slug receiving and positioning means, which attachment may be readily and quickly applied to the usual outside galley when short length slugs are to be cast and which can be readily removed therefrom when slugs of the usual length are to be cast and thus avoid impairing the normal operation of the galley while slugs of the usual length are being cast.

To these and other ends, the invention consists in certain improvements and combinations and arrangements of parts all as will be hereinafter more fully described, the features of novelty being pointed out particularly in the claims at the end of the specification.

In the accompanying drawings:

Figure 1 is a perspective view of the slug receiving end of an outside galley, equipped with short length slug receiving means embodying the present invention;

Figure 2 is a top plan view of the structure shown in Figure 1; and

Figure 3 is a detail vertical section taken on the line 3-3 of Figure 2.

Similar parts are designated by the same reference characters in the different figures.

The present invention is applicable generally to line casting machines of the class disclosed in the Mergenthaler patent hereinbefore referred to and to the so-called "outside" galleys used on such machines to receive the type bars or slugs cast in the machine as such slugs are ejected through the usual ejecting passage by the ejecting means commonly used in such machines. Since the construction and mode of operation of line casting machines of this class are well understood by those skilled in the art, it is deemed sufficient to show and describe the slug ejecting portion of the machine which comprises usually a forwardly and rearwardly reciprocatory ejector blade 1 which is carried on the usual mold slide 2 on which the usual mold wheel 3 is mounted, this ejector blade

moving forwardly through the casting cavity of the mold 4 on the mold wheel, when such mold is brought in the usual way to ejecting position, the ejector blade also passing forwardly between the usual trimming knives 5 and through the ejecting passage 6 in front of them, whereby the slug S cast in the mold is pushed forwardly through the mold and between the trimming knives and then 10 through the slug ejecting passage 6, from which point the slug passes to the galley, it being understood that the slug when ejected from the mold and pushed forwardly by the ejector blade stands in vertical position, it resting on one end on the bottom wall 7 of the ejecting passage 6, the type face or character bearing edge T of the slug being at its forward edge.

15 The outside galley commonly used in line casting machines of this class comprises a galley plate 8 and brackets 9 which support the plate in a forwardly and downwardly inclined position in front of the framework of the machine, a downwardly and forwardly inclined chute plate 9^a extending from the bottom wall 7 of the ejecting passage to the upper rear edge of the galley plate 8 so that slugs of the usual length, when pushed beyond the forward end of the ejecting passage, will slide downwardly endwise over the chute plate 9^a onto the galley plate 8 and, in so doing, will become turned by the usual pivotally suspended gate 9^b so that their upper ends are tipped rearwardly while their lower ends are deflected forwardly, the type faces on the slugs being thus brought into uppermost position as these slugs are deposited on the galley plate, the mode of operation of an outside galley of this type being described in detail in U. S. Letters Patent No. 1,464,483 granted Aug. 7, 1923, to T. S. Homans. 20 designates the usual slide or abutment against which the slugs are stacked and 11 represents the usual slug lever which moves toward the abutment, after each slug 25 has been delivered to the galley, to advance the stack of slugs and provide a space to receive the next following slug.

While such outside galleys as heretofore used are capable of successfully handling slugs of the usual lengths, they are incapable of handling slugs of short length, such as those less than 8 ems in length, so that the type faces of such short slugs when deposited in the galley will be directed upwardly, it having been found that in ejecting slugs less than 8 ems in length from the usual ejecting passage of the machine, such slugs will not be tipped rearwardly at their upper ends, 30 as is the case with slugs of 8 ems or more in length, with the result that short length slugs would be deposited in the galley with their type faces arranged vertically at their forward edges and hence out of printing position.

The present invention provides means, preferably in the form of an attachment for the usual outside galley, whereby short length slugs cast in the machine may be ejected in the usual manner from the usual 75 ejecting passage of the machine and will be deposited in the galley with their type faces directed upwardly, thus avoiding the necessity of casting these slugs of greater length than required by the type faces thereon and 80 of subsequently cutting off the excess portions of such slugs as heretofore practised.

85 In the construction shown in the present instance, a chute 12 is provided which comprises a pair of parallel vertical plates 13 and 14 spaced apart a distance sufficient to receive and permit the slugs to travel longitudinally between them, the bottom of the chute being closed by a bottom strip 15 which extends between and is secured to the lower edges of the plates 13 and 14. The slug receiving end of the chute is adapted to be positioned in alignment with the slug ejecting passage 6 of the machine, the plate 13 being arranged for this purpose beyond or in front of the usual 90 bracket plate 16 while the plate 14 of the chute is arranged at the inner side of the usual stationary bracket plate 17, and the chute is provided with a clamp 18 which is adapted to fit removably over the upper edge 95 of the stationary bracket plate 17 and is provided with a screw 19 by means of which it may be detachably secured to the plate 17. The bottom strip 15 of the chute is arranged to overlie the usual chute plate 9^a, and when 100 the chute is in position, the rear end of the bottom strip 15 will be substantially level with the bottom wall 7 of the slug ejecting passage. The lower forward end of the chute is provided with a block or post 20 which is secured between the plates 13 and 14 and thus closes the forward end of the chute, and the lower end of this block is formed with a lug 21 which is adapted to abut against the flange or lip 8^a on the lower edge of the galley 110 plate, a ledge 22 extending rearwardly from the lug 21 and resting on the flange 8^a. The chute 12, when in operative position, is inclined forwardly and downwardly so that the short length slugs will slide forwardly and 115 downwardly therein by gravity, and in order to avoid damaging the type faces of these slugs which are foremost while such slugs are descending in the chute, a facing 23 of leather or other relatively soft yielding material is 120 provided at the inner side of the block or post 20 to arrest the descent of the slugs.

The chute 12 for the short length slugs overlies the galley plate 8, and an opening 24 is provided in the bottom of the chute, as 125 by terminating the bottom strip 15 at a suitable distance in advance of the slug arresting facing 23, through which the slugs may drop from the chute 12 onto the galley plate. This opening is controlled by a shutter 25 130

which is pivoted at 26 to the underside of the bottom strip 15 so that it may swing into and out of position beneath the opening 24. The forward or free edge of the shutter 25 extends to a position in proximity to the rearwardly extending ledge 22, which latter defines the forward end of the opening 24, and this ledge 22 extends rearwardly beyond the facing 23 to form an overhang or shelf, as will be clear from Figure 3. The shutter 25 is provided with a spring 27 which acts to swing the shutter into a position to uncover the opening 24, and means is provided, which is actuated by the normal movement of a part of the machine, for moving the shutter, at appropriately timed intervals, into position to close the opening 24, such means consisting in the present instance of a rod 28 which is pivotally connected at one end to an arm 29 on the shutter and is bent at its rear end as indicated at 30 so that it will rest freely against the forward edge of the usual bracket 31 which forms part of the ejector slide adjusting means and which bracket is carried by and moves with the mold slide 2. The intermediate portion of the rod 28 may be guided by a bracket 32 attached to the galley bracket plate 17 and having an open-top bearing to removably receive and slidably guide said rod. By this arrangement, the shutter 25 will be normally in a position to uncover the opening 24 in the slug chute 12 while the mold slide 2 is in its normal rear position but when the mold slide moves forwardly preparatory to operation of the ejecting mechanism to eject a slug from the mold, the shutter will be swung into position to close the opening 24 by the consequent forward movement of the rod 28, and when the mold slide recedes or moves rearwardly following the slug ejecting operation, the rod 28 will be allowed to move rearwardly and the shutter will then be swung into position to uncover the opening 24 under the action of the spring 27.

sage 6 and the lower end of the chute having the lug 21 thereon resting on the upturned flange of the galley plate so that the lower portion of the chute overlies the galley plate, and the rod 28 is placed in the open-top bearing in the bracket 32, it resting by gravity therein, so that its rear end 30 will be engaged by the bracket 31 connected to the forwardly and rearwardly reciprocatory mold slide 2. With the chute 12 thus superposed on the galley, each slug pushed forwardly and ejected from the ejecting passage 6 by the advance of the ejector blade 1 will be brought into position on the bottom rail 15 of the chute, the slug standing vertically on end and having its type face or printing edge foremost. The slug will then slide by gravity down the bottom rail 15 until its forward edge or type face strikes the buffer or yielding abutment 23 as indicated by the full lines in Fig. 3. Preceding the ejecting of the slug, the mold slide 2 advances as usual, and this forward movement or advance of the mold slide carries the bracket 31 from the dotted line position to the full line position shown in Fig. 2, thereby pushing the rod 28 forwardly and causing the shutter 25 to swing into position to close the opening 24 in the bottom of the chute. Consequently, when the slug reaches the abutment 23, it will rest on the shutter 25 which will then be closed, the forward edge of the slug however resting on the ledge 22 which is located slightly beyond the forward or free end of the shutter. When the mold slide 2 recedes or moves rearwardly, following the ejecting operation, as is usual in machines of this class, the bracket 31 will be returned from the full line position to the dotted line position shown in Fig. 2, thus allowing the rod 28 to move rearwardly under the action of the spring 27, as the result of which the shutter 25 is swung from beneath the opening 24, thus removing its support from the slug resting thereon. However, while the rear portion of the slug will be thus relieved

The operation is as follows:

While operating the line casting machine for the casting of slugs of the usual lengths, the chute 12 is omitted from the galley, the 50 relatively long slugs then discharging from the usual ejecting passage 6 onto the guide plate 9^a and tipping rearwardly at their upper ends while sliding endwise into the galley so that they are received by the galley plate 8 in upright position with their printing edges 55 facing upwardly. In order to enable short slugs cast in the machine to be properly received in the galley, the chute 12 is superimposed on the galley as shown in Fig. 1, the pivoted gate 9^b being first lifted to admit the chute, after which the gate may rest idly on top of the chute as indicated in Fig. 1, and the chute is removably secured in position by the clamp 18 and screw 19, the upper end of 60 the chute being aligned with the ejecting pas- 35

of the slug will rest upon the relatively fixed ledge 22, so that the rear portion of the slug will swing downwardly by gravity through the opening 24 while the ledge 22 supports the forward edge of the slug, in consequence of which the slug will be turned edgewise while dropping by gravity through the opening 24, and the slug will be deposited on the galley plate 8 with its printing edge or type 115 face uppermost. Immediately after the shutter 25 has moved into open position to cause dropping of the slug into the galley, the slug lever 11 operates in the usual way to push the slug against the other slugs already contained in the galley and to advance the stack of slugs a short distance to provide space into which the next following slug may drop. 120

When the casting of short slugs is to be discontinued and the casting of slugs of the usual 125 130

When the casting of short slugs is to be discontinued and the casting of slugs of the usual 130

length resumed, the chute 12 is removed from the galley whereupon the slugs of usual length cast in the machine and ejected through the usual ejecting passage will be received in the 5 galley in the manner usual with outside galleys.

I claim as my invention:

1. In a galley for line casting machines, a galley entrance embodying means for sustaining a slug in standing position on one of its ends while travelling therein, and means for turning the slug edgewise to bring its type face uppermost.
2. In a galley for line casting machines, a 15 galley entrance embodying means for sustaining a slug by an edge thereof for edgewise travelling movement therein while its type face is foremost, means for arresting such travelling movement of the slug, and means 20 for turning the slug edgewise to bring its type face uppermost.
3. In a galley for line casting machines, a galley entrance embodying a chute for supporting a slug on one of its ends while travelling therein, means in the chute for arresting the slug against further travel, and means 25 for discharging the slug from its arrested position in the chute into the galley and for turning the slug to bring its type face uppermost.
4. In a galley for line casting machines, a galley entrance forming a chute for supporting the slug on one of its ends while travelling therein, the bottom of said chute having 30 an opening for the discharge of the slug therethrough into the galley, and means controlling said opening and operative to turn the slug to bring its type face uppermost while discharging through said opening.
5. In a galley for line casting machines, a 35 galley entrance embodying a chute to receive and slidably support a slug while resting on one of its ends, the bottom of the chute having an opening for the discharge of the slug therethrough into the galley, a relatively 40 fixed part to support one edge of the slug above said opening, a withdrawable part to support the rest of the slug, and means for withdrawing the latter part to discharge the slug into the galley and to cause turning of the 45 slug to bring its type face uppermost.
6. In a galley for line casting machines, a galley entrance to support a slug while travelling therethrough and having an opening for 50 the discharge of the slug therethrough into the galley, and means actuated from a moving part of the machine for controlling said discharge opening.
7. In a galley for line casting machines, a 55 galley entrance to support a slug on one of its ends while travelling therethrough and having an opening for the discharge of the slug therethrough, and means actuated by a moving part of the machine for releasing the slug for discharge through said opening.

and for turning it during such discharge to bring its type face uppermost.

8. In a galley for line casting machines, a galley entrance embodying a chute for supporting a slug on one of its ends while travelling 70 therethrough and having an opening in its bottom for the discharge of the slug therethrough into the galley, means for arresting the travel of the slug when it reaches a position above said opening, a member movable 75 into position to support the slug above said opening and withdrawable to cause dropping of the slug therethrough into the galley, and a part to cooperate with the slug while discharging through said opening to bring its 80 type face uppermost.

9. In a galley for line casting machines, having slug ejecting means and a forwardly movable slide for bringing the same into position for operation, a galley entrance 85 embodying a chute to receive a slug from the ejecting means and to support it on one of its ends while travelling therein, means for discharging the slug from said chute into the galley and for turning the slug to bring 90 its type face uppermost, and means actuated by the advance of said slide for operating said slug discharging and turning means.

10. In a galley for line casting machines, a galley entrance embodying a chute for supporting a slug to travel therein with its type face foremost, the bottom of the chute having an opening for the discharge of the slug therethrough into the galley, a stop in said chute beyond said opening for arresting the 100 travel of the slug, a ledge at one end of said opening adjacent to said stop for supporting the forward edge of the slug, and a member beneath said opening and movable into a position to uncover said opening and cause 105 the slug to drop therethrough while its forward edge rests on said ledge and thereby cause turning of the slug to bring its type face uppermost.

11. In a galley for line casting machines, embodying a plate to receive type slugs with their type faces uppermost, a galley entrance embodying a chute having means for removably mounting it above said plate, said chute being adapted to receive and support 110 slugs on their ends and having an opening above said plate for the discharge of the slugs therethrough onto said plate, and means for turning the slugs to bring their type faces uppermost while discharging through said 115 opening.

12. In a galley for line casting machines, embodying a plate to receive type slugs with their type faces uppermost and having an entrance for directing slugs thereto while 120 their type faces are uppermost, an entrance having means for removably mounting it in superposed position above the galley plate and the first-mentioned entrance and embodying a chute for receiving and sup- 125

porting slugs while resting on their ends, and means for turning the slugs from said chute to bring their type faces uppermost and for discharging them onto the galley

5 plate.

In testimony whereof I have hereunto set my hand.

EDMUND M. GOODBODY.
